Inventor,

Robert L. Horsley,

By *A. D. Jackson,*
Attorney.

UNITED STATES PATENT OFFICE.

ROBERT L. HORSLEY, OF FORT WORTH, TEXAS, ASSIGNOR TO WORTH WIRE WORKS, OF FORT WORTH, TEXAS, A CORPORATION OF TEXAS.

FENCE-STAY.

No. 805,071.

Specification of Letters Patent.

Patented Nov. 21, 1905

Application filed January 4, 1905. Serial No. 239,638.

To all whom it may concern:

Be it known that I, ROBERT L. HORSLEY, a citizen of the United States, residing at Fort Worth, Texas, have invented a new and

5 Improved Fence-Stay, of which the following is a specification.

This invention relates to fences, and more particularly to stays for bracing the line-wires of fences where the lines are constructed 10 of two or more strands twisted together; and the object is to provide a stay which will prevent vertical movement of the line-wires relative to each other and which cannot be moved longitudinally on the line-wires; and 15 a further object is to provide a stay which can be put on easily and quickly without any special tool and which requires no tie or binding wire to hold the same in place.

Other objects and advantages will be fully 20 explained in the following description, and the invention will be more particularly pointed out in the claims.

Reference is had to the accompanying drawings, which form a part of this specification.

25 Figure 1 is a side elevation of a section of a fence provided with the improved stay. Fig. 2 is an enlarged view of a section of a stay, illustrating how the stay is adjustable so that 30 it may be applied to line-wires of different sizes.

Similar characters of reference are used to indicate the same parts throughout both views.

35 The improved stay is applicable to any fence constructed of line-wires composed of two or more strands twisted together.

The stay is composed of two wires or rods formed into spirals. One of the wires A may 40 be placed on the wires of the fence, and then the other wire B may be inserted from the top by screwing it down in the spiral of the wire A. The wires A and B engage the line-wires C and D at points where one of the 45 strands of the line-wires is directly above the other, so that the space between the wires A and B is required to be equal only to the diameter of one of the strands composing the line-wires C and D. One of the wires A or B 50 may be passed between the strands of the line-wires, as shown at E. Both the wires A and B can be screwed down at the same time and made to engage the line-wires. The line-wires may or may not be provided with 55 barbs. When the stays have been adjusted to their proper places, the ends of the wires

A and B are bent down and partly around the top line-wire, as shown at the left of Fig. 1. The wires A and B may or may not be fastened to the bottom line-wire.

60

In the drawings one of the stays projects below the line-wire and one is fastened to the bottom line-wire. One of the advantages of this improved stay is that it may be adjusted to adapt the same for use on different sizes of line-wire.

65 The practice will be to manufacture the stays so that they will be adapted to the largest size line-wires.

When it is necessary, the stays can be adjusted to smaller wires by fastening one of the stay-wires and then moving the other stay-wire until it engages the line-wires closely and rigidly.

70 Fig. 2 shows the stay engaging large wires. D. The dotted outline shows how the wire A may be moved longitudinally to adapt the stay for use on a smaller wire, as shown in dotted lines at a. When the wire A has been moved longitudinally for the purpose, it may 80 be secured in the adjusted position by bending the upper end about the top line of the fence.

Having fully described my invention, what I claim as new, and desire to secure by Letters Patent, is—

1. A stay for fences and similar objects comprising two wires formed into spirals of similar mesh whereby one of said wires may be screwed on the wires of a fence and secured thereto and then the other wire screwed into the mesh of the first wire and made to engage the wires of the fence.

90 2. A stay for fences and similar objects comprising two wires formed into spirals and meshing with each other and provided with ends thereof adapted to engage the top line-wire of a fence, either of said wires being adjustable longitudinally relative to the other whereby said stay is adapted to engage line-wires of different sizes.

95 3. The combination with the line-wires of a fence having wires of two or more strands, of a stay for said fence consisting of two wires formed into spirals and one wire 105 screwed into the mesh of the other and engaging said line-wires and having the ends at one end of said stay bent to engage one of the line-wires.

110 4. The combination with the line-wires of a fence having the wires thereof composed of two or more strands twisted together, and

stays therefor composed of two wires formed into spirals and screwed on said line-wires, said stay-wires inclosing in the mesh thereof the said line-wires at points where strands of 5 the line-wires are one above the other.

5. The combination of the line-wires of fences or similar objects and stays therefor, said stays consisting of two wires screwed on said line-wires and one of said wires screwed 10 into the mesh of the other and having the

ends thereof bent about the top line-wire of the fence, the line-wires of the fence being composed of strands twisted together.

In testimony whereof I set my hand, in the presence of two witnesses, this 24th day 15 of December, 1904.

ROBERT L. HORSLEY.
